UNITED STATES PATENT OFFICE.

MARTIAL REDON, OF LIMOGES, FRANCE.

DESIGN FOR A COVERED DISH.

SPECIFICATION forming part of Design No. 23,213, dated April 24, 1894.

Application filed September 20, 1893. Serial No. 486,035. Term of patent 7 years.

To all whom it may concern.

Be it known that I, MARTIAL REDON, a citizen of France, residing at Limoges, in the Republic of France, have invented and produced 5 a new and original Design for Covered Dishes, of which the following is a specification.

In the accompanying drawings Figure 1, shows a face view of the cover of a dish embodying my new design. Fig. 2, shows a perspective view of a dish embodying my new design.

The essential features of my design, consist in a cover composed of a series of segmental sections, the outer borders of which are partly 15 ornamented with an arabesque leaf ornament, and partly with an escaloed edge; the escaloed edge forming the boundary of a portion, and the arabesque leaf ornament another portion; where the arabesque leaf forms the boundary, an escaloed ornamentation is placed 20 within the arabesque border; these escaloops merge gradually into the plain exterior of the cover; at the back part of the cover two shell shaped ornamentations C' C' are arranged 25 one upon either side of the convoluted center ornamentation d. From this ornament d a series of indentations d' d' arise, and are finally merged into the plain surface of the cover; a line of bead ornamentation accentu-

ates the segmentation of the cover, the handle 30 on the cover is a raised arabesque ornamentation. The dish proper Fig. 2, is ornamented with vertical rows of bead ornamentation and arabesque leaf work, the handle on either side being ornamented with a combination of bead 35 and arabesque ornamentation. The character of the ornamentation is such, that it conforms to that of the covered dish, which has one slightly convex side C, and the other portions conforming more to a circular or clam 40 shape.

In the drawings A is the plain surface of the dish or cover, A', the escaloed ornamentation, A² the bead ornamentation, A³, the arabesque leaf ornament. 45

B are the handles.

C' is the shell shaped ornament.

D are the segmental lines.

d is the center ornament.

d' are indentations which merge into A. 50

I claim—

The design for a covered dish substantially as herein shown and described.

MARTIAL REDON.
